(57) **CLAIM**

We claim the ornamental design for a teardrop shaped diffuser ring, as shown and described.

DESCRIPTION

FIG. 1 is a front perspective view of the teardrop shaped diffuser ring;

FIG. 2 is a front elevational view of the teardrop shaped diffuser ring;

FIG. 3 is a rear elevational view of the teardrop shaped diffuser ring;

FIG. 4 is a side elevational view of the teardrop shaped diffuser ring;

FIG. 5 is a side elevational view of the opposed side of the teardrop shaped diffuser ring;

FIG. 6 is a bottom view of the teardrop shaped diffuser ring; FIG. 7 is a top view of the teardrop shaped diffuser ring; and, FIG. 8 is a bottom rear perspective view of the teardrop shaped diffuser ring.

The broken line showing of a base is included for the purpose of illustrating environmental structure and forms no part of the claimed design.
